FIG. 1 is a front perspective view of a luggage case showing my new design;

FIG. 3 is an end elevational view thereof, the end opposite that shown being the same in appearance; and

The rear of the luggage case is the same in appearance as the front.

The characteristic feature of my design resides in the straps which extend longitudinally of the top wall of the case intermediate the marginal welting and at right angles downwardly over the upper portions of the end walls of
